UNITED STATES PATENT OFFICE.

WALTHER FÄHNDRICH, OF HAMBURG, GERMANY, ASSIGNOR TO CLIFFORD WILLIAM KEMP, OF BIRMINGHAM, ENGLAND.

SUSPENSION-LAMP.

SPECIFICATION forming part of Letters Patent No. 657,486, dated September 4, 1900.

Application filed March 23, 1900. Serial No. 9,918. (No model.)

To all whom it may concern:

Be it known that I, WALTHER FÄHNDRICH, manufacturer, a subject of the Emperor of Germany, residing at Neustrasse, Hamburg, in the Empire of Germany, have invented certain new and useful Improvements in Suspension-Lamps, of which the following is a specification.

This invention relates principally to suspension gas-lamps, and has for one of its objects to arrange the metallic suspension fittings with the gas-supply pipes in such a manner that they are removed from the influence of the products of combustion arising from the burner of such lamps, so that such fittings when made of polished brass or the like are not liable to be tarnished or discolored by the ascending heat and fumes, as now commonly occurs in suspension-lamps. Another object is to facilitate the removal and replacement of the globe or shade, while a third object is to so arrange the suspension arms or pipes that they are disposed inside the globe, by which a novel and elegant appearance is imparted to the lamp.

Figure 1 of the accompanying drawings represents a side elevation of a suspension gas-lamp constructed and arranged in accordance with my invention, but with the globe or shade and its detachable support shown in section. Fig. 2 is a front elevation of the said lamp with the same parts in section. Fig. 3 is a front elevation of the lamp, showing how the globe or shade is introduced into position from below and also showing the detachable support of the lamp in section and separately. Fig. 4 represents a view of a lamp in which only a single suspension-arm is employed. Fig. 5 is a view, partly in side elevation and partly in section, showing a stop-cock fitting in longitudinal section.

The same letters of reference indicate corresponding parts in the several figures of the drawings.

In the construction represented in Figs. 1, 2, and 3, *a* is a terminal fitting in connection with a gas-supply, being either a suitable wall patras or a part of a chandelier, and has proceeding from it a branched or bifurcated bracket *b*, from the separated terminations *b'*

of which a hanger consisting of a pair of suspension-arms *c* depends and is connected at its lower end *c'* to the casing or body part *d* of a stop-cock, into which a plug *d'* is fitted for controlling the supply of gas to a superimposed burner *e*, carrying a gallery *f*, upon which the chimney *g* rests. This chimney is disposed in the middle of the lamp and between the branched or spreading members of the bracket *b*, which are so disposed relative to the exit to the chimney that the products of combustion arising from the latter are delivered clear of the said suspension members. Either one or both of the branches and suspension-arms constitutes a gasway for supplying the burner with gas.

Surrounding and inclosing both the burner with its chimney and the suspension-arms is a globe or shade *h*, carried by a separable support *i*, having a seat for the globe and detachably connected to a wormed neck *d''* of the stop-cock casing *d* by means of a screwed collar *i'*, forming a part of the said support, which said collar is of sufficient diameter internally as to clear and admit of passing over the turn *d'''* of the stop-cock plug *d'*. It will thus be seen that the suspension-arms *c* are disposed between the chimney and the globe, which latter, with its support, is introduced into position around the arms and chimney from below when the support is removed (see Fig. 3) and is retained or held in its proper position, as shown in Figs. 1 and 2, by screwing the support, as aforesaid, onto the neck of the stop-cock casing.

It is obvious that instead of supporting the burner, chimney, and globe of the lamp by bracket branches and suspension-arms arranged in duplicate, as in Figs. 1 to 3, the said parts may equally be supported by a single bracket member *b* and suspension-arm *c*, as represented in Fig. 4, with the said arm *c* still coming between the outer shade *h* and chimney *g*, or the single suspension-arm may proceed direct from a suitable terminal instead of depending from a branch or bracket, as shown.

In the drawings I have shown the preferred manner of detachably connecting the support to the lamp, but except in so far as specific-

ally mentioned in the following clauses of claim my invention is not confined to that preferred form.

While I have shown specifically herein a particular form of stop-cock fitting, it is to be understood that I do not limit my invention or claims to that particular form; but it is merely illustrative of one suitable arrangement of stop-cock fitting.

Having fully described my invention, what I desire to claim and secure by Letters Patent is—

1. In suspension-lamps, the combination with a double-armed or branched bracket, of a hanger consisting of a pair of depending arms arranged to come between the globe and the chimney of the lamp, and terminating in a burner-fitting, to which a support for the said globe is detachably secured to admit of the globe being introduced into position from below, substantially as and for the purpose herein described and also as set forth in the accompanying drawings.

2. In suspension-gas-lamps, the combination with a double-armed or branched bracket, of a hanger consisting of a pair of depending arms arranged to come inside the globe and between it and the chimney and provided with a gasway, and terminating in a stop-cock casing, to which a support for the said globe is detachably secured to admit of the globe being introduced into position from below, substantially as and for the purpose herein

described and also as set forth in the accompanying drawings.

3. In suspension-lamps, the combination with a bracket or support, of a hanger coming between the globe and chimney of the lamp and terminating in a burner-fitting, to which a globe-support is detachably secured to admit of the said globe being introduced into position from below, substantially as herein described, and also as set forth in the accompanying drawings.

4. In a suspension-lamp, the combination with a double-armed or branched bracket, a hanger consisting of a pair of depending arms arranged to go between the globe and the chimney of the lamp, a burner-fitting supported by said hanger and provided with a screwed neck, a chimney arranged over the burner-fitting, a support having a detachable screw connection with the screwed neck of the burner-fitting and provided with a seat for the globe, and a globe resting in said seat, all so arranged that the globe may be introduced into position from below, substantially as described.

In testimony whereof I have hereunto set my hand in presence of two subscribing witnesses.

WALTHER FÄHNDRICH.
